UNITED STATES PATENT OFFICE.

FRANK J. BRANDEL AND FRANK H. RICHERT, OF BUFFALO, NEW YORK.

UPHOLSTERY SPRING.

Application filed March 10, 1921. Serial No. 451,416.

To all whom it may concern:

Be it known that we, FRANK J. BRANDEL and FRANK H. RICHERT, citizens of the United States, residing at Buffalo, in the 5 county of Erie and State of New York, have invented certain new and useful Improvements in Upholstery Springs, of which the following is a specification.

Our invention relates to springs such as 10 are, or may be used in car seats and backs, upholstered furniture, cushions and the like for supporting the upholstery, and belongs to that class of spring units which have straight lengths forming the side of one or 15 more V's, and having small coils at their apices, in place of the usual spiral springs.

One object of our invention is to provide 20 a spring unit which will have practically a vertical movement, and being so constructed as to fold upon itself without touching its different parts will operate without rubbing or squeaking. Its opposite coil eyes being connected the spring unit cannot be pushed out of shape, and sets of 25 spring units being fastened in series they cannot get out of alignment.

With these and various other objects in 30 view our invention consists in certain features of construction hereinafter specified and claimed, reference being had to the accompanying drawings forming a part of this specification.

Like numerals of reference indicate like 35 parts in all the figures of the drawings.

Figure 1 is a front elevation of our improved spring unit.

Fig. 2 is a side elevation of the same with 40 a portion of webbing attached to the top for connecting a series of spring units.

Fig. 3 is a plan of the same with the webbing of Fig. 2 shown dotted and the bottom of the spring unit attached to frame wires.

Fig. 4 is a perspective view of our spring 45 showing it mounted at the bottom on frame wires, the bottom members attached to a webbing for connecting a line of spring units, and the top attached to a webbing, as on Figs. 2 and 3, to connect spring units in parallel lines.

Fig. 5 is a plan of a frame showing the 50 method of attaching our spring units and the method of connecting them at top and bottom by webbing.

It is understood that spring units of a 55 somewhat similar shape forming a portion

of our present spring and connected together have been used, but they lack resiliency and ability to keep their shape, which are the principal features of our invention.

The spring unit as shown is made of a single piece of wire the center length of which is at the top on center line A—A and formed into a transverse T-shaped loop at 14 for attaching and holding the webbing 19 by means of a webbing strip 20 and rivets 21, 21, etc. This is for the purpose of anchoring the top of the spring unit and giving it only an up and down motion.

From the loop 14 the spring unit is formed of duplicate straight side members 13—13, 11—11, 9—9, 7—7, 5—5 and 3—3, each pair, as 13—13, etc., being symmetrical with and on opposite sides of the center line A—A of Figs. 1 and 3. These straight members are connected at their apices by coil eyes 12—12, 10—10, 8—8, 6—6 and 4—4 ending with coil eyes 2—2, and as shown in Figs. 2, 3 and 4. The contiguous straight members, as 13—13, 11—11, and 11—11, 9—9, etc., form V shaped 75 duplicate springs extending diagonally from the top to the bottom, except the lower straight members 3—3 which are horizontal.

The apices 12—12, 10—10, 8—8 and 6—6 are held from spreading when the spring 85 unit is compressed by means of the rods 18, 17, 16 and 15. These rods are passed through the said apices and held in place by means of a head on one end and a nut on the other. It is understood that rods 17 and 18 may be left out, as the occasion may 90 require.

As will be noted in Fig. 3, the spring is 95 so formed that the coil eyes of the horizontal base wires form approximately the corners of a square and the remaining coil eyes are each more disposed toward the center of said square than the previous lower coil eyes so it can be compressed flat upon itself and the side members and apices with their holding 100 rods will telescope into each other without touching, as in both front and side views, (Figs. 1 and 2) and the spring tapers in both directions toward the top. The loop portion 14 projects over the rods 17, 15 and frame 1, but cannot come into contact with them 105 as the webbing 19 is threaded through the loop 14 and forms a buffer on the apices 6, 6. It is understood that this loop 14 can be moved forward or back, or bent up to clear frame 1 if necessary, although it is in- 110

tended that sufficient strength and resiliency will be incorporated in the springs so they will never be compressed quite flat.

In Fig. 5 is shown the application of the 5 spring units in rows and connected to a frame 1, 1, 1 and 1, the outside member 1 being bent at right angles to form the end member 24, to which the remaining inside members 1, 1 and 1 are attached at their 10 ends.

The spring units are mounted side by side and in rows on parallel frame members 1—1 and 1—1. The lower members 3, 3, and 3, 3 of the spring units, which are side 15 by side, are connected to each other by means of a webbing 22, and a webbing strip 23, riveted to said webbing for each of said members 3, 3, etc. The webbing 22 is fastened at its ends to the opposite side 24 of 20 the frame and so holds the spring units stationary sideways, which the top webbing 19 running across the spring units to front and rear preserve their cross alignment.

We do not limit ourselves to the one series 25 of top webbing 19, but may use another top webbing at right angles to, and fastened to webbing 19.

We do not limit ourselves to the arrangement 30 and construction shown, as the same may be varied without departing from the spirit of our invention.

Having described our invention what we claim and desire to secure by Letters Patent is:

35 1. An upholstery spring of the class described, being composed of parallel rows of spring units arranged and supported on parallel wires in pairs, each of said units being composed of duplicate pairs of spring

wires oppositely disposed about a center line 40 and with V shaped portions having coil eyes at the apices of each V, each of said duplicate pairs forming a unit and being held together by means of rods through said coil eyes and independent of the other units, 45 each of said units converging upward in both front and side views and means to anchor said units to each other at their tops by webbing in one direction and to each other at their bases by webbing at right angles to 50 said first direction.

2. An upholstery spring unit of the class described, having a base composed of two horizontal spring wires with coil eyes for support on parallel wires of a frame, said 55 base and frame wires forming approximately the sides of a square and the base coil eyes being at the corners thereof, said unit being composed of duplicate pairs of spring wires oppositely disposed about a center line at right angles to said frame 60 wires and rising from said base wires diagonally upward and forward and back to form V shaped spring portions having coil eyes at the apices of each V, each of said 65 duplicate pairs of wires being tied together by means of rods through said last named coil eyes, and each of said spring portions above said base being more disposed toward the center line of said unit than the one 70 below it, whereby the tying rods become successively shorter toward the top of said unit.
